SKI BINDING

Ernst R. Keller, Springfield, Mass., assignor to
 Dartmouth Co-Operative Society, Inc., Hanover,
 N. H., a corporation of New Hampshire

Application February 9, 1938, Serial No. 189,630

3 Claims. (Cl. 280—11.35)

This invention relates to improvements in skiing apparatus and has for its principal objects the provision of a simple yet improved ski-binding having adjustable toe irons which are adapted to 5 snugly and efficiently fit shoes of various sizes.

According to one object of the invention, the apparatus includes a novel combination and arrangement of parts characterized by its simplicity and relatively low cost of production. Thus, as 10 a special feature, the device is particularly adapted for use by children in that the device is both readily attachable to a ski and the toe irons are readily adjustable for accommodating shoes of various sizes, yet the cost is low so that they are 15 within the range of economy consistent with children's sporting goods.

According to another feature of the invention, the device is formed to include a plate member which is secured to the ski and is adapted to 20 co-operate with toe iron members, which are adjustable relative thereto.

Various other novel features and advantages of the invention will be hereinafter more fully referred to in connection with the accompanying 25 description of the preferred form of the invention, reference being had to the accompanying drawing wherein:

Fig. 1 is a plan view of the ski-binding device of the invention shown secured to a ski;

Fig. 2 is a side elevational view of the construction shown in Fig. 1; and

Fig. 3 is a sectional view on the line 3—3 of Fig. 1.

Referring now to the drawing more in detail, 35 the invention will be fully described.

A plate member is shown at 2 and this is preferably formed of a sheet of more or less flexible metal. The plate has its forward end portion secured to the upper side of a ski S, as by screws 40 4 shown in Fig. 1. If desired, there may be a plate part 5 over member 2 through which screws 4 extend.

The body part 2 is somewhat elongated and extends rearwardly from where it is secured to the 45 ski S. A heel member 6, which is adapted to fit around the back of the heel of the shoe, is preferably carried by and secured to the rear end portion of plate member 2, as by rivets or screws 8.

What I call toe iron members are provided and 50 these include upwardly extending side portions 10 and horizontal body parts 12. Each of the body parts 12 has an opening (not numbered) adjacent its forward end and another, indicated by 14, adjacent its rear end.

55 The plate member 2 is provided with two

spaced-apart rows of spaced openings 16 and two other spaced-apart rows of spaced openings 18. The openings 16 of each row are in alignment with one another as well as with the corresponding openings 16 of the other row of the pair, while 5 the openings 18 of each row are likewise in alignment with one another as well as with the corresponding openings 18 of the row opposite it.

According to the preferred form of the invention, the rows of openings 16 are placed forwardly 10 of the rows of openings 18. Also the rows 16 are nearer together than are the rows 18, all for a purpose which will presently appear.

In the assembling of the apparatus, the plate parts 12 are placed upon the plate 2 with the 15 forward openings thereof coinciding with any selected and aligned pair of openings 16. Then screws 20 extend through the forward openings of parts 12, into the chosen pair of openings 16 of the plate, and then into the ski S. 20

It will be appreciated that in this way, the locating and adjustment of the toe irons relative to the plate member is made possible. That is, by selecting the desired pair of openings 16, the toe irons may be attached to the plate at the 25 desired distance from heel member 6.

The openings 14, which are somewhat elongated and larger than the openings 16, are so located as to be adapted to coincide with a certain pair of openings 18 when the forward ends 30 of the parts 12 are secured to plate 2. Then adjusting screws 22 extend into openings 14, through the openings 18, and into the ski and in this way the irons are held in place with the upstanding parts 10 disposed at various angles 35 relative to one another and relative to the longitudinal centerline of the ski, depending upon the location of screws 22 with respect to elongated openings 14.

Preferably the parts 12 are formed to have 40 downwardly projecting lips or flanges 24 around holes 14, as shown in Fig. 3. This is for elevating the parts 12 more or less so that screws 22 will be substantially flush with the planes of the parts 12 and thus not interfere with the 45 fit of the shoe thereon.

It is desirable that each part 10 be provided with an opening, such as 26, for receiving a shoe strap of usual form. Also, the heel member 6 may have associated therewith a loop 50 member such as 28 for receiving another strap in the usual manner.

From the above it will be seen that the toe irons may not only be readily adjusted relative to the heel member 6 to accommodate shoes of 55

various lengths but the irons may be adjusted angularly with respect to one another to accommodate shoes of varying widths. The adjustment is easy to accomplish and the construction is simple so as to be readily attached to the ski. This together with the fact that the cost of the device is low renders the construction of the invention particularly suitable for children.

10 While I have described the invention in great detail with respect to a preferred form thereof, what it is desired to claim and secure by Letters Patent of the United States is:

15 1. The combination with a ski of a ski-binding device comprising in combination, a plate secured at its forward end to said ski provided with separate sets of spaced openings, a shoe engaging member having an opening in its forward end to register with any one of the openings of one set thereof, and provided with an opening in its rear end to register with one of the openings of the other set, and screws in the openings, which are in register to clamp the shoe engaging member and plate together and hold the same in adjusted relation and against relative movements.

20 2. The combination with a ski of a ski-binding device comprising in combination, a plate secured at its forward end to said ski provided

25 with separate rows of openings, a shoe engaging member on said plate having an opening in its forward end for registering with any opening in one row of openings in said plate and a slot in its rear end for registering with an opening of the other row of openings in the plate, screws in the openings which are in register, all adapted and arranged whereby the shoe engaging member may swing on the screw in the opening at the forward end thereof and be clamped to said plate in different relative positions.

3. The combination with a ski of a ski-binding device comprising, a longitudinally-extending plate member having its forward end secured to said ski, said plate member being provided with an inner pair and an outer pair of spaced-apart longitudinally-extending substantially parallel rows of spaced openings, a pair of shoe-engaging members provided with openings in their forward and rear end portions, screws extending through said forward openings in the shoe-engaging members and into certain of the openings in said inner rows, and other screws extending through said rear openings in the shoe-engaging members and into certain of the openings in the outer rows.
